UNITED STATES PATENT OFFICE

134,621

DESIGN FOR A SLICED BREAD DISPENSER

Willis M. Wright, Dearborn, and Frank F. Wahl,
Monroe, Mich.

Application October 28, 1942, Serial No. 108,624

Term of patent 7 years

To all whom it may concern:

Be it known that we, Willis M. Wright, a citizen of the United States, residing at Dearborn, in the county of Wayne and State of Michigan, and Frank F. Wahl, a citizen of the United States, residing at Monroe, in the county of Monroe and State of Michigan, have invented a new, original, and ornamental Design for a Sliced Bread Dispenser, of which the following is a specification, reference being had to the accompanying drawing, forming a part thereof.

We claim:

The ornamental design for a sliced bread dispenser, as shown.

WILLIS M. WRIGHT.
FRANK F. WAHL.
